FIG. 1

FIG. 2

FIG. 3

Figure 1 is a top plan view of the combined spoon and fork showing our new design.

Figure 2 is a side elevation.

Figure 3 is a front elevation.

The characteristic feature of our design resides in the outline configuration of the bowl portion, combined with the arrow-shaped fork point at the extremity thereof, all as shown.

We claim:

The ornamental design for combined spoon and fork, as shown and described.
